US00D551619S

(12) **United States Design Patent** (10) **Patent No.:** **US D551,619 S**
Schneider (45) **Date of Patent:** **** Sep. 25, 2007**

(54) **ELECTRICAL DRIVE UNIT**

(75) Inventor: **Johannes Schneider**, Kirchlengern (DE)

(73) Assignee: **Linak A/S**, Nordborg (DK)

(**) Term: **14 Years**

(21) Appl. No.: **29/216,694**

(22) Filed: **Nov. 8, 2004**

(30) **Foreign Application Priority Data**

May 6, 2004 (DK) ..... DA 2004 00149

(51) **LOC (8) Cl.** **13-02**

(52) **U.S. Cl.** **D13/110**

(57) **CLAIM**

The ornamental design for an electrical drive unit, as shown and described.

DESCRIPTION

FIG. 1 is a top perspective view of an electrical drive unit showing my new design;

FIG. 2 is a bottom perspective view thereof,

FIG. 3 is an elevational left side view thereof,

FIG. 4 is a top plan view thereof,

FIG. 5 is an elevational right side view thereof,

FIG. 6 is a bottom plan view thereof,

FIG. 7 is an elevational front end view thereof; and,

FIG. 8 is an elevational rear end view thereof.

1 Claim, 3 Drawing Sheets

FIG. 1

FIG. 2

FIG. 3**FIG. 4****FIG. 5****FIG. 6****FIG. 8****FIG. 7**
